Philip H. Robbins Inventor,
By Verma E. Hedges Atty.

UNITED STATES PATENT OFFICE.

PHILIP H. ROBBINS, OF NEW YORK, N. Y., ASSIGNOR TO POIRETTE CORSETS, INC.,
OF NEW YORK, N. Y., A CORPORATION OF NEW YORK.

CORSET.

Application filed December 13, 1923. Serial No. 680,539.

To all whom it may concern:

Be it known that I, PHILIP H. ROBBINS, a citizen of the United States, residing at New York, in the county of New York and 5 State of New York, have invented certain new and useful Improvements in Corsets, of which the following is a specification.

This invention relates to an improvement in corsets, and one object of the invention 10 is to combine the brassière and corset into one garment.

Another object of the invention is to so construct the combination brassière and step-in-corset, requiring only a twelve inch 15 garment where ordinarily a fourteen inch garment would be necessary, and a fourteen inch garment where a sixteen inch garment would ordinarily be necessary, due of course to design.

20 Another object of the invention is to construct the brassière in two parts forming a front and back part, hooked together at the sides.

Another object of the invention is the 25 elastic or non-elastic connection between the inner lower ends of each half of the brassière to the corset proper.

Another feature of the invention is that 30 the design of the front of the corset part forming a restraining part of the brassière, likewise with the back of the garment.

In the drawings:

Fig. 1 is a perspective view showing the front of the garment;

35 Fig. 2 is a perspective view showing the back of the garment;

Fig. 3 is a detail view showing the manner of securing the inner lower ends of the brassière to the corset.

40 The numeral 1 indicates the non-elastic body or back portion of the corset, the numerals 2 and 3 indicate rear elastic sections attached to the vertical edges of the non-elastic body or back portion. These elastic 45 portions 2 and 3 are preferably provided with stays 4—4 at the meeting edges of the back 1 and non-elastic sections 2 and 3. Connected to the rear elastic sections 2 and 3 are the front elastic sections 5 and 6, which extend toward the front and are connected to the front non-elastic panel 7. At 50 the meeting edge of the front non-elastic section 7 and the elastic sections 5 and 6 stays 8—8 are provided which begin a short distance from the top edge and extend

downwardly to approximately the center of the corset.

The front non-elastic section 7 is preferably provided with a plurality of stays 9 centrally thereof, the lower portion of said sections being open as at 10, and provided with a lacing 11. The upper part of both the front and back non-elastic sections 7 and 1 extend slightly above the upper edge of the elastic sections as illustrated. The 65 lower edge of the corset is provided with the usual fastening means 12, for supporting the stockings.

The brassière is preferably made in front and back sections 13 and 14, secured at the 70 lower edge to the upper edge of the front and back non-elastic sections 7 and 1, the remaining lower edge of the brassière being free relative to the side elastic portion of the corset. The front and back sections 75 of the brassière are adapted to be fastened together at the sides as at 13' and 14'. On each side of the brassière adjacent the securing means are elastic strips 15 which extend downwardly diagonally, the lower 80 ends being secured to the elastic sections of the corset at their meeting edge. The elastic strips serve to permit free movement of the body and yet hold the brassière down, neatly around the body. The numeral 16 85 indicates the usual shoulder straps of the brassière. Loops 17 are provided at the sides of the corset to enable the wearer to pull the same up into the correct position.

It will thus be seen that I have combined 90 the corset and brassière into a single slip on garment, the brassière being divided at the sides to facilitate the application of the garment, the construction being such that the garment fits very neatly, and the brassière at all times is held in place. The fact that the brassière and corset are not attached at sides permits each movement of the body, the elastic fastening means for the detached sides serving to keep the brassière in 100 place.

I claim:

1. In a garment of the character described, the combination with a corset including elastic and non-elastic sections, of 105 a brassière secured to the non-elastic sections of the corset, the lower side portions being formed into extensions, the upper edges of the side elastic sections and the extensions overlapping each other, and 110

means for attaching said extensions to the elastic sections below the upper edges thereof.

2. In a garment of the character described, the combination with a corset including elastic and non-elastic sections, of a brassière secured to the non-elastic sections of the corset, the lower side portions of the brassière being formed into extensions which underlap the upper edge of the side elastic sections, and means for attaching said extensions to the elastic sections below the upper edge thereof.

3. In a garment of the character described, the combination with a corset, of a brassière secured thereto, the lower side portions of the brassière and the upper edge of the corset overlapping each other, and elastic strips secured to the lower edges of the brassière and attached to the corset for holding the sides of the brassière and corset together.

4. In a garment of the character described, the combination with a corset, of a brassière secured thereto, the lower side portions of the brassière extending beneath the upper edge of the corset, and elastic strips secured to said lower underlapped edges of

the brassière and secured to the corset for holding the sides of the brassière within the corset.

5. In a garment of the character described, the combination with a brassière having openings on each side thereof, of a corset connected with the brassière and having front, back and side sections secured together, and elastic strips secured adjacent the edges of the openings in the brassière and connected with the sections of the corset for holding the sides of the brassière within the corset.

6. In a garment of the kind described, the combination of a one-piece body portion made of front and back sections, of a non-elastic material and side sections of elastic material, a brassière consisting of front and back sections secured to the non-elastic sections of the body portion and strips secured adjacent the meeting edges of the front and back portions of the brassière, the lower ends of which are secured intermediate of the top and bottom of the body portion.

In testimony whereof I affix my signature.

PHILIP H. ROBBINS.
